UNITED STATES PATENT OFFICE

KENNETH E. CROOKS, OF WILLIAMSPORT, PENNSYLVANIA

MATERIAL GUIDING MEANS FOR WOODWORKING MACHINES

Application filed October 26, 1927. Serial No. 228,842.

This invention relates to certain new and useful improvements in material guiding means for wood working machines and is especially adapted to be used in connection with the Yates disc head matcher, the object being to provide means for positively guiding the strip of material past the rotating cutting head so that the difficulties now existing with machines of this character will be eliminated.

Another object of my invention is to provide a guide which has a positive engagement with the material so that the strip in passing the gap of the cutter head is positively guided and held against the adjustable guide of the machine whereby the chipping off of the ends of the strips are eliminated.

Another object of my invention is to provide a guide which is preferably in the form of a knife which is adapted to embed itself in the material being operated on so that the strip is positively engaged and held at the proper distance from the rotating cutting head.

Another and further object of the invention is to provide one form of guide which is yieldably held into engagement with the material so that it can move up and down to accommodate itself to the irregularities of the material being operated on.

A still further object of the invention is to provide a guide which not only guides the material and prevents lateral movement thereof, but also holds the material down on the bed of the machine so as to prevent the ends from moving upwardly when they are in engagement with the cutters of the head.

A still further object of the invention is to provide a guide which is so constructed that it can be attached to the ordinary hood of the Yates matcher so that the weight of the hood will apply the proper pressure on the knife in order to hold it into engagement with the material being operated on and to exert pressure on the material in order to hold the end of the material as it comes into engagement with the knives of the cutter firmly against the bed and adjustable guide of the machine.

Another object of my invention is to provide guiding means for the material being

operated on in a wood working machine which is in the form of a knife so disposed in respect to the rotary cutter that it will embed itself in the material in its passage therethrough by pressure exerted directly by the 55 knife or by pressure exerted on the material in order to provide positive means for guiding the strip of material as it passes the cutter.

Other and further objects and advantages of the invention will be hereinafter set forth 60 and the novel features thereof defined by the appended claims.

In the drawings,

Figure 1 is a top plan view of a portion of a Yates A—7 disc head matcher showing the 65 application of my improved construction of pressure bar and guide;

Figure 2 is a detail side elevation partly in section showing the hood carrying one of the guides in raised position;

Figure 3 is a detail view showing the knife 70 in its engagement with one of the strips as it passes the cutting head;

Figure 4 is a detail end view of the hood and cutting knife showing the relative position of the knife in respect to the material being operated on;

Figure 5 is a detail perspective view of the knife detached;

Figure 6 is a detail perspective view of one 80 corner of the hood showing the adjustable set screw for limiting the downward movement of the hood which also controls the depth of the cut made by the knife for guiding the strip;

Figure 7 is a detail enlarged section through a portion of the knife showing the same in engagement with the strip arranged between the guide;

Figure 8 is a detail vertical section showing a modified form of knife in which the holder is bifurcated to receive the cutting blade; the holder forming a pressure bar for exerting pressure on the top of the strip in order to hold it down as it passes the cutter;

Figure 9 is a detail view showing the knife with its beveled cutting edge arranged in opposite position to that shown in the preferred form;

Figure 10 is a detail vertical section of a slightly modified form of knife;

Figure 11 is a detail section of still another modified form of knife and pressure bar;

5 Figure 12 is a detail vertical section through still another form of knife;

Figure 13 is a detail top plan view showing the preferred manner of mounting the knife so that the line contact of the knife is slightly diagonal to the movement of the strip in order to have the tendency to force it against the adjustable guiding means;

Figure 14 is a detail perspective view of a strip showing the groove formed by the knife 15 for guiding the same and the strip after it passes through the tongue forming mechanism of the machine so that the groove is cut away as the tongue is formed on the strip;

Figure 15 is a side elevation of a portion 20 of a wood working machine showing the hood and upper guides raised and a knife guide disposed on the bed thereof;

Figure 16 is a top plan view of the same;

Figure 17 is a detail view showing the knife 25 inserted in the bed and the same embedded in the under side of a strip in its passage therethrough; and

Figure 18 is a detail section through a modified form of knife and pressure bar in which 30 the cutting edge is formed on an arc of a circle.

In the embodiment of my invention as herein shown I have illustrated a portion of the Yates disc matcher, which machine operates on a strip of material so as to produce a strip of flooring, one face of the strip being finished by a rotating cutting head mounted on a horizontal axis and provided with knives which engage the strip on the upstroke 35 of the head, the head being arranged in the usual manner so that the cutting face of the head is not perfectly parallel with the face of the strip being operated on whereby the knives only cut on the upward movement of 40 the head.

In the drawings 1 indicates the bed of the machine which is provided with yieldable guides 2 and 3 between which is arranged a cutter head 4 carried by a shaft 5 mounted in a suitable bearing 6. Arranged to one side of the bed are driven feed rollers 7 and 8. Movably mounted on the other side of the bed 1 is a movable table 9 carrying feed rollers 10 and 11 and provided with a guide 12 50 against which the strip of material travels in passing the rotating cutting head, said table being adjustably mounted by means of a lever 13 in the usual manner.

The end of the shaft 5 is engaged by thrust 55 bearing 14 carried by arm 15 mounted on a shaft 16.

The above construction is only described in a general way in order to make the operation of my improved construction of guide 60 clear, and is in accordance with the ordinary

Yates A—7 disc head matcher, well known in the art.

Pivottally mounted on the shaft 16 is a hood 17 adapted to enclose the rotary cutting head and to which is preferably connected the usual air conveyor for conveying the chips and dust away from the cutter, this construction being omitted so that the position of the knives and guide can be more clearly shown. 70

This hood carries an adjustable set screw 18 for limiting the downward movement of the hood and said set screw is adapted to engage a fixed portion of the body of the machine. By pivotally mounting the hood as described, it can be swung back into the position as shown in Figure 2 in order to allow the cutter to be reached in order to remove the jams caused by the flexing and breaking of the strips in passing through the machine. The weight of the hood holds the same down 80 and allows it to move up and down as the strip passes through the machine as will be later described.

In order to increase the pressure of the hood on the material when operating on certain grades of material, the hood is provided with a bifurcated lug 19 between which is adapted to pass a pivoted rod 20 carrying a spring pressed member 21 for applying the proper tension to the hood. 85

In the embodiment of my invention I have shown the rear portion of the general construction of Yates hood cut away to receive a bearing 22 of a bifurcated arm 23 in which is mounted a weighted member 24 by a pair 90 of bolts 25 whereby when one of the bolts is removed, the other bolt will act as a pivot and allow the member to swing therein for the purpose hereinafter fully described.

The member 24 carries a pressure bar and 95 guide 26 which is adapted to engage the top of the strip to the rear of the cutter so as to guide the strip past the rear portion of the cutter in order to prevent it from being injured and the particular construction of 100 110 guide is substantially the same as the other form of guide which will hereinafter be later described.

The form of guide as shown in Figure 5 consists of a holder 27 which is adapted to be bolted within the hood as shown in Figures 2 and 3 by bolts 28 so that it can be adjusted up and down in respect to the usual gauge carried by the hood as shown in Figure 2. This holder plate is preferably provided with 115 a rabbeted edge in which is bolted the guiding knife 29 by bolts 30, the knife being preferably formed with a beveled cutting edge as shown in Figure 3 which is adapted to engage the top of the strip and to embed itself therein when the hood is in the position shown in Figure 1 so that a positive guide is formed for the free end of the strip as it passes the cutter and at the point where the cut is being made. 120 125 130

The knife guide 29 is formed with a toe portion 29¹ and a heel portion 29² in order to provide a bevel portion which is adapted to be engaged by the edge of the strip so that strips with turned up ends will not jam in passing under the guide. When operating on high grade material, the pressure exerted by the cutting edge of the guide is sufficient to hold the strips on the bed and against the adjustable guide without any additional pressure exerting means.

In order to prevent any danger of the knives 26 and 29 from moving laterally so that they by any cause will be brought into engagement with the knives of the cutter head, I provide the shaft 5 on which the head is mounted with a washer 31 so disposed that the ends of these two knives when moved towards the cutter by any cause will engage the washer and limit the movement of the knives so that it will be impossible for the knives to be brought into engagement with the cutters of the head.

In order to form additional means for limiting the knife 29 I provide the same with an adjustable set screw 32 which is adapted to engage a fixed portion of the bed of the machine to limit the lateral movement of the knife in respect to the cutter.

In setting the knives and especially the knife 29 which is arranged opposite the working cutters of the head, I preferably have the cutting edge of the knife arranged slightly out of a horizontal plane so that the point of the knife is in a plane below the rear edge of the knife whereby as clearly shown in Figure 3, the knife when operating on a good grade of stock, only embeds itself half of its length in the material being operated on.

I also preferably arrange this knife as shown in Figure 13 diagonally to the movement of the strip or in other words, the knife is not parallel with the guide 12 so that as the knife embeds itself in the upper edge of the strip being operated on, it has the tendency to force the strip and positively hold it against the guide 12.

While I have shown a knife preferably mounted in this manner, I am, of course, aware that it can be mounted in various other ways and the same result will be accomplished so long as the knife travels in a groove either formed by the knife or a previous groove formed by a cutter. This is to distinguish my invention from the ordinary pressure bar which frictionally engages the top of the strip in an attempt to eliminate the chipping off of the ends of the strips by the cutters as they pass therethrough.

Prior to my invention the hood of a Yates disc matcher carried what was known in the art as a hold down, which frictionally engaged the top of the strip being operated on and was supposed to prevent the strip from

being drawn laterally by the cutters of the head away from the adjustable guide.

While I have shown means for positively forming a groove in the strip being operated on by the guiding means itself, I do not wish to limit myself to the use of a cutting guide as I am aware that a groove could be made in the strip previous to it being operated on by the head and by having a guide member fitting in the groove thus formed, lateral movement of the strip will be prevented.

In the construction shown in Figure 8, 40 indicates the hood, 41 a holder having a bifurcated lower portion in which is adjustably secured a knife 42 which extends downwardly below the edge of the holder so that after the knife has embedded itself within the edge of the strip, the holder exerts pressure on the top of the strip in order to hold it down on the bed of the machine.

In the modification shown in Figure 9, the knife 43 has its beveled edge arranged on the opposite side of that shown in the preferred form.

In the modification shown in Figure 10 I have illustrated a knife 44 having a V-shaped cutting edge.

In the modification shown in Figure 11, I have a pair of knife holders and pressure bars 45 and 46, each having a knife 45' and 46' extending below the lower edge thereof so that the material is engaged by two cutting edges and two pressure bars in order to hold it properly as it passes the cutter.

In the modification shown in Figure 12, I illustrate a cutter 47 having two cutting edges 48 and 49.

In order to provide means for holding the strip firmly on the bed so as to prevent vertical and lateral movement of the strip as it passes the cutter, it is essential that said means be yielding in order to allow said means to adjust itself to the irregularities of the strip being operated on and I have found in practice that by attaching a pressure bar with a knife edge to the hood of the ordinary Yates matcher in place of the ordinary hold down now in use, that I am able to eliminate a large percentage of the chipping off of the ends of the strips in passing through the machine.

In the Yates machine as shown in Figure 2, there is substantially a four to ten inch gap where the material is free to move towards the cutter when an ordinary hold down is used as it is impossible to exert enough friction on the moving strip to hold it against the set guide on the opposite side of the guide way from the cutter, especially in view of the fact that the strips are not uniform as some of the strips turn laterally and others vertically at the ends and the strips that turn laterally are drawn into the cutter so that the chipping off of the face of the strip is very pronounced and in manufacturing

flooring the portion chipped off has to be cut from the finished strip.

While in the drawing I have shown a combined pressure bar and guide especially adapted to be used on a Yates machine constructed for manufacturing tongue and groove flooring of a V-shaped formation, it is, of course, understood that I do not wish to limit myself to the use of my guide in connection with a particular construction of machine as it is capable of being yieldably mounted on a machine in various ways so that the strip is positively held against the adjustable guide so that it can not be drawn into the cutters as they rotate with the head.

In the embodiment of my invention as shown in Figures 15, 16 and 17, 50 indicates the bed of the machine which is provided with the usual feed rollers and a rotary cutting head 51. The machine is provided with the usual hood 52 to which is connected a guide 53.

The hood is mounted to swing on a shaft 54 on which is mounted an arm 55 carrying a guide 56, this construction being substantially the same as previously described.

The bottom of the bed opposite the gap formed by the cutting head is provided with a knife guide 57 which is adapted to engage the bottom of the strip in its passage therethrough as shown in Figure 17 so as to guide and hold the strip against the adjustable guide 58.

While I have shown this knife guide used in connection with the upper guides, it is, of course, understood that the upper knife guides could be removed and a suitable hold-down or pressure bar placed on the pivoted hood so that the pressure of the hood against the top of the material would force it into engagement with the guide 57 so that this guide would cut or embed itself into the lower edge of the strip in its passage therethrough in order to prevent it from moving laterally and to hold it against the adjustable guide 58.

In Figures 15, 16 and 17 I have illustrated the guide 57 when used in connection with a Yates disc head matcher, but, it is, of course, understood that this guide can be used in connection with various other forms of wood working machines and that when disposed on the bed of the machine and used in connection with a pressure bar to hold the material down, the material will be forced against the knife so that the knife will embed itself in the material and prevent the material from moving laterally.

While I have shown this guide knife arranged in a certain position on the bed of the machine, it is, of course, understood that it can either be formed integral or as a separate element and secured in position within a suitable holder arranged within the bed so that it can be removed and sharpened and therefore I do not wish to limit myself to any

particular manner of mounting this knife guide as I am aware that it can be mounted in various ways without departing from the spirit of my invention.

I am also aware that this knife guide can be used in connection with upper knife guides as clearly shown so that not only the lower edge of the strip will be held against lateral movement, but the upper edge of the strip will also be held against lateral movement, so that the strip in its passage therethrough cannot be drawn into the cutter so as to chip the end thereof in its passage therethrough.

In the modification shown in Figure 18, I show a knife 60 which has its cutting end formed on an arc of a circle so as to produce a combined pressure bar and knife.

In the operation of a machine having a yielding guide, a strip of flooring is fed between the feed rollers 7, 8, 10 and 11 and between the yieldable guides 3 and the adjustable guide 12 which is predeterminedly set so that a predetermined cut will be made on one face of the strip as it passes the cutter. As the strip reaches the gap formed by the cutter, it is positively engaged by the cutting guide, the knife embedding itself within the edge of the strip and positively holding the same against the set guide. As this guide is carried by the hood, it is held into engagement with the edge of the strip by the weight of the hood and if necessary, additional pressure can be applied through the medium of the spring pressed member 21 carried by the rod 20.

In order to prevent the end of the strip from engaging the other half of the cutter, the guide 26 is employed and by having the same carried by a support pivotally mounted on a shaft which support is weight-ed, it is also yieldably held into engagement with the strip so that this guide enters the groove previously cut by the guide 29 and continues to guide the strip until it has passed the cutter. By having the same mounted in this particular manner as shown and described, by loosening one of the bolts the knife is free to swing on the other bolt as a pivot which allows the knife to be swung upwardly past the cutter so that a piece of material which has jammed in the machine can be removed. This is true in respect to knife 29 and is of a great advantage when used in connection with a Yates matcher as it is essential that these knives be movably mounted so that they can be swung out of the way in order to remove strips which have jammed in the machine.

In the operation of a fixed guide used in connection with a pressure bar, as the material is fed through the machine, it is forced into engagement with the fixed knife guide so that the knife embeds itself in the under side of the material in order to positively engage the same so as to prevent lateral move-

ment of the material as it passes the rotary cutter.

While I have shown and described the use of three guiding means, I have found in practice that a single guide carried by the hood and of the construction as shown which will engage the edge of the strip and guide it past the center of the cutter, is sufficient to eliminate the majority of chipping off of the strips.

I am also aware that the fixed guide as well as the movable guide could be arranged diagonal to the path of the material in its passage therethrough so that these guides which positively engage the material by embedding themselves therein have a wedging action on the material to force it against the wall of the guide ways of the machine.

While in the specification I have shown and described my improved construction of guiding means used in connection with a

Yates matcher, I am, of course, aware that the same can be used in connection with any form of wood working machine where it is necessary to guide the material being operated on and therefore I do not wish to limit myself to the use of my improved construction of guiding means to any particular construction of wood working machine.

From the foregoing description, it will be seen that I have provided a guide for a wood working machine which positively engages the strip so as to prevent lateral movement thereof and while I have shown certain details of construction, I am aware that various changes can be made without departing from the spirit of my invention as clearly defined in the claims, as my invention consists broadly in providing means for positively engaging the strip to prevent lateral movement thereof in its passage by the cutting head.

What I claim is:—

1. In a machine of the kind described, the combination with a guide way for guiding a strip of material in its passage lengthwise therethrough, of a rotary cutting head adapted to operate on one side of said strip in its passage therethrough, and knife guides pivotally mounted above said guide way and to each side of the axis of said cutter for positively guiding the strip of material being operated on by said cutter.

2. In a machine of the kind described, the combination with a guide way for guiding a strip of material in its passage therethrough, said guide way having a gap formed in one wall thereof, of a rotary cutter mounted on a horizontally disposed shaft adapted to operate in the gap of said guide way, a member extending outwardly from the cutting face of said cutter surrounding said shaft and a yieldable guide mounted to engage the upper edge of said material for positively guiding the material past said cutter, said member forming a stop for said guide.

3. In a machine of the kind described, the combination with a guide way for guiding a strip of material lengthwise in its passage therethrough, a rotary cutter operating on one face of the strip in its passage through said guide way, a movable holder mounted in advance and to the rear of said cutter and guide blades carried by said holders for engaging the material in its passage therethrough for preventing vertical and lateral movement of the material.

4. In a machine of the kind described, the combination with a guide way for guiding a strip of material in its passage therethrough, a rotary cutter operating on one face of the strip in its passage therethrough, a pivoted hood for said cutter, an adjustable holder carried by said hood and a cutting blade carried by said holder for engaging and guiding a strip of material in its passage therethrough.

5. In a machine of the kind described, the combination with a guide way for guiding a strip of material in its passage therethrough, said guide way having a gap, a rotary cutting head arranged to one side of said guide way having a portion thereof working in said gap, a movably mounted hood arranged over said cutting head, adjustable means for limiting the downward movement of said hood, a holder adjustably mounted on said hood and a knife carried by said holder adapted to engage the upper edge of the strip of material in its passage therethrough for positively guiding said strip past the face of said cutting disc.

In testimony whereof I hereunto affix my signature.

KENNETH E. CROOKS.
